US0D1061895S

(12) **United States Design Patent** (10) **Patent No.:** **US D1,061,895 S**
(45) **Date of Patent:** **** Feb. 11, 2025**

(54) **PORTABLE INTRAORAL SCANNING DEVICE**

(71) Applicant: **Align Technology, Inc.**, San Jose, CA (US)

(72) Inventors: **Zakhar Ginzburg**, Netanya (IL); **Roe Gorfinkel**, Yavne (IL); **Tom Seatter**, Tel Aviv (IL); **Ariel Shalev**, Beit Shemesh (IL)

(73) Assignee: **Align Technology, Inc.**, San Jose, CA (US)

(**) Term: **15 Years**

(21) Appl. No.: **29/768,563**

(22) Filed: **Jan. 29, 2021**

(51) LOC (15) Cl. **24-01**

(52) U.S. Cl.

USPC **D24/158**

(58) **Field of Classification Search**

USPC D24/158-161, 185-187, 107, 145, 176, D24/177

CPC .. A61B 5/05; A61B 5/055; A61B 6/03; A61B 6/035

(57) **CLAIM**

The ornamental design for a portable intraoral scanning device as shown and described.

DESCRIPTION

FIG. 1 is a front left perspective view of a portable intraoral scanning device with the handle in a first position in accordance with the claimed design.

FIG. 2 is a rear left perspective view thereof.

FIG. 3 is a front view thereof.

FIG. 4 is a rear view thereof.

FIG. 5 is a right side view thereof.

FIG. 6 is a left side view thereof.

FIG. 7 is a top view thereof.

FIG. 8 is a bottom view thereof.

FIG. 9 is a rear left perspective view of a portable intraoral scanning device with the handle in a second position in accordance with the claimed design.

FIG. 10 is a front view thereof.

FIG. 11 is a rear view thereof.

FIG. 12 is a right side view thereof.

FIG. 13 is a left side view thereof.

FIG. 14 is a top view thereof; and,

FIG. 15 is a bottom view thereof.

The broken lines in the figures show portions of the portable intraoral scanning device that form no part of the claimed design.
